FIRE ALARM BOX

Fred O. Johnson, Northport, N.Y., assignor to American District Telegraph Company, Jersey City, N.J., a corporation of New Jersey

Filed Apr. 3, 1967, Ser. No. 6,495

Term of patent 14 years

(Cl. D72—1)

FIG.1.

FIG.2.

FIG.3.

FIG.4.

FIG.5.

FIG.7.

FIG.6.

FIG.8.

FIG.9.

FIG.10.

FIG.11.

FIG.12.

FIG.14.

FIG.13.

FIG. 1 is a front elevational view of a fire alarm box embodying my design.

FIG. 2 is a front elevational view similar to FIG. 1, but showing the fire alarm box in operated conditions.

FIG. 3 is a right-side elevational view of the fire alarm box of FIG. 1.

FIG. 4 is a rear elevational view of the fire alarm box of FIG. 1.

FIG. 5 is a top plan view of the fire alarm box of FIG. 1.

FIG. 6 is a bottom plan view of the fire alarm box of FIG. 1.

FIG. 7 is a cross sectional view taken along the line 7-7 of FIG. 1.

FIG. 8 is a front elevational view of a modified fire alarm box embodying my design.

FIG. 9 is a front elevational view similar to FIG. 8, but showing the fire alarm box in operated condition.

FIG. 10 is a right-side elevational view of the fire alarm box of FIG. 8.

FIG. 11 is a rear elevational view of the fire alarm box of FIG. 8.

FIG. 12 is a top plan view of the fire alarm box of FIG. 8.

FIG. 13 is a bottom plan view of the fire alarm box of FIG. 8.

FIG. 14 is a cross sectional view taken along the line 14-14 of FIG. 8.

The dominant features of my new design reside in the portions shown in full lines.

I claim:

The ornamental design for a fire alarm box, as shown and described.
